RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY

METHOD OF AND MEANS FOR STABILIZING REFRIGERANTS

Application filed June 17, 1926. Serial No. 116,512.

This invention relates to heat transforming systems and particularly to the stabilizing of the working substances by which the thermodynamic effects are produced. The 5 invention includes both a method and the means by which the method is practiced.

It has been observed that few if any working substances known or used as refrigerants remain permanently unaltered during long 10 periods of operation. Even non-electrolytes such as carbon tetrachloride, methylene chloride, the methyl and ethyl chlorides, etc. tend to hydrolyze in time due to the presence of traces of moisture, and to liberate traces of 15 chlorine which may attack metals. It has been suggested to place in contact with the vapor of such refrigerants hygroscopic substances such as calcium chloride which are supposed to dry the vapor and the liquid 20 which results from the condensation of the vapor to a point which should prevent hydrolysis. I have found such methods unsatisfactory since with sufficient hygroscopic material present to dry the vapor enough of 25 it passes with the vapor throughout the system to deposit a film of water moist material on the metal parts and accelerate rather than prevent corrosive effects.

Among the objects of the invention are to 30 inhibit decomposition of working substances, to prevent harmful effects from slight decomposition of such substances, to devise suitable means for accomplishing the above objects, and in general to improve prior methods and 35 apparatus. Other objects will be apparent from the detailed description which follows:

Instead of attempting to dry the refrigerant in situ as heretofore proposed, my invention consists in starting with the refrigerant as dry as possible and then preventing 40 decomposition or the harmful effects of such action by my improved method which comprises acting upon the refrigerant while in liquid state so as to prevent the formation 45 of hydroxyl and to neutralize any acids which may form. To this end basic oxides such as calcium oxide (CaO), barium oxide, magnesium oxide, etc. may be used, also the corresponding hydroxides, such as calcium hydroxide (CaOH), etc. Suitable means are

provided for bringing such substances into direct contact with some or all of the liquid bodies of the working substance in the system.

In order to illustrate the invention and the 55 manner of its operation one concrete embodiment thereof is shown in the accompanying drawings, in which:

Fig. 1 is a somewhat diagrammatic view of 60 a refrigerating system, certain of the parts of which are partly cut away or shown in section;

Fig. 2 is a side elevational view on an enlarged scale of a container for the moisture absorbing or acid neutralizing material; and 65

Fig. 3 is an end elevational view of the container shown in Fig. 2.

The heat transforming system indicated 70 diagrammatically in Fig. 1 is of the closed cycle type comprising an evaporator or refrigerating element 4 (disposed in a suitable chamber or refrigerator A), a pump or compressor 5 withdrawing vapor from the evaporator 4 through a pipe 6 and discharging the vapor at a higher temperature and pressure 75 through a pipe 7 into a condenser 8 where heat is extracted from the circulated working substance through a cooling medium which may be either air or water, the condenser discharging into a chamber 9 in which the condensate is collected, whence extends a conduit 80 10 which discharges into evaporator 4 through a suitable throttling member or expansion device 11. The working substance occurs in liquid form particularly in evaporator 85 4 and in chamber 9.

The working substance may be a liquid 90 having a low boiling point of the type used in conventional systems operating on the Clausius-Rankine cycle, such as ammonia or sulphur dioxide, or physical mixture of a volatile liquid and a gas substantially inert to and insoluble in the liquid and in its vapor as disclosed and claimed in my copending application, Serial No. 603,998, filed November 29th, 1922, operating in accordance with the process disclosed in my copending application Serial No. 15,172, filed March 12, 1925, or a lubricating refrigerant of the type disclosed in my copending application Serial 100

No. 60,311, filed October 3, 1925, operating in accordance with the processes set forth in my copending applications Serial No. 85,580, filed February 2, 1926 and Serial No. 88,164, filed February 15, 1926. The invention particularly relates, however, to working substances having as their major component a non-electrolyte such as carbon tetrachloride, methylene chloride, the methyl and ethyl chlorides comprising the substances known as chlorinated methyl and chlorinated ethyl derivatives.

In accordance with my improved process the working substance is maintained in a stable condition and the harmful effects of decomposition are avoided by bringing the liquid refrigerant into contact with suitable material for absorbing moisture and for neutralizing any acids which may form as a result of the tendency on the part of the refrigerant to hydrolyze. To this end suitable chemicals which are strongly alkaline and which have an affinity for free moisture are utilized. Compounds suitable for this purpose are the basic oxides, such as the oxides of calcium, barium, magnesium, etc., also the hydroxides, resulting from the combination therewith of water in either its liquid or vapor state. A preferred way to effect contact of the liquid refrigerant with such compounds is to immerse the latter in the liquid refrigerant. This is best accomplished by placing the stabilizing material in a suitable container having perforated walls, or preferably made entirely of reticulated material of fine mesh. Figs. 2 and 3 illustrate a container 12 of this kind which is shown as cylindrical in form but may be of any other desired shape and arranged to contain lumps 13 of the stabilizing material, such as calcium oxide (CaO).

Containers 12 may be inserted in the heat transforming system wherever the working substance occurs in liquid form. In Fig. 1 such containers are disclosed as immersed in the liquid in evaporator member 4 and in the liquid in chamber 9. Since there is more or less dilution of the working substance by lubricant from the lubricating system and of the lubricant by refrigerant from the refrigerating system, it is also well to place a container 12 with stabilizing material therein in the lubricant body. In Fig. 1, such a container is shown as immersed in the sump of the crank case 5a of compressor 5. When lubricating refrigerants are utilized the evaporator or refrigerating element 4 may have a concentrating chamber 4a in which a body of the lubricating refrigerant gathers and one of the containers 12 for the stabilizing material is preferably placed therein.

In the system shown the working substance or refrigerant may have as its volatile liquid component, for example, methylene chloride and as its gaseous component air.

The lubricant in the sump of compressor 5 may be a heavy oil or a thin grease having a paraffin base and the lumps of stabilizing material 13 may be substantially pure and dry calcium oxide. Starting with the methylene chloride in evaporator 4 the vapor of the same together with the air in the evaporator is drawn off by compressor 5 and discharged into condenser 8 where the vapor is liquefied and collects in chamber 9 whence it passes through pipe 10 and expansion valve 11 back into the evaporator. In the form shown in Fig. 1, free moisture is removed from the working substance so as to maintain it in a substantially "dry" and stable condition at any desired number of spaced points as in chambers 4a and 9, respectively. Any lubricant which works over into the refrigerating system is also maintained in a substantially "dry" and stable condition by the action of the calcium oxide in container 12 in the sump of the compressor. The combining of moisture with the calcium oxide produces calcium hydroxide (CaOH). Any acid which may result from decomposition of either the liquid refrigerant or of the lubricant will be promptly neutralized through the action of the strongly basic calcium oxide or its hydroxide. Thus if chlorine is liberated from methylene chloride, it will combine with the calcium oxide to form calcium chloride (CaCl₂). The quantity and area of stabilizing material should be sufficient to cause the law of mass action to operate—that is, there should be a large excess of basic material over that theoretically calculated to complete the reactions indicated. When this is done the inhibiting effect of the method is more complete. The containers 12 are by preference formed of metal screen cloth of fine mesh to retain and confine the chemical enclosed thereby.

From the above it will be apparent that the method of stabilizing working substances herein disclosed operates through removing all free moisture from both the circulated working substance and from any other substance which may be mingled therewith by intent or leakage and by promptly neutralizing all acid products of decomposition, that the effects sought are readily obtained by placing suitable chemical materials in contact with the liquid working substance, and that the enclosing of such chemicals in suitable containers prevents the dissipating of the chemicals through the system and facilitates the renewal of the active ingredients.

While but one form of the invention has been herein shown and described it is to be understood that the invention is not limited to the specific details thereof but covers all changes, modifications, and adaptations within the scope of the appended claims.

I claim as my invention:

1. In a heat transforming system involv-

ing the change of state of a liquid capable of reacting with water, the method of inhibiting said reaction which consists in repeatedly bringing said liquid into contact with a substance adapted to supply hydroxyl ions thereto.

2. The method of stabilizing refrigerants of the chlorinated hydrocarbon type which comprises bringing the liquid refrigerant repeatedly into contact with a basic oxide.

3. In a heat transforming system utilizing methylene chloride as the working substance, the method of maintaining the latter in stable condition which comprises repeatedly bringing the working substance in liquid state into contact with a basic oxide.

4. The method of stabilizing refrigerants of the chlorinated hydrocarbon type which comprises bringing the liquid refrigerant repeatedly into contact with substantially pure and dry calcium oxide.

5. In a heat transforming system utilizing methylene chloride as the working substance, the method of maintaining the latter in stable condition which comprises repeatedly bringing the working substance in liquid state into contact with substantially pure and dry calcium oxide.

6. In the method of producing heat transforming effects by circulating in a closed cycle a working substance which occurs in liquid and in vapor states in various parts of the cycle, that step in the method which comprises subjecting the working substance while in liquid state to the action of a basic oxide to extract moisture from the working substance.

7. In the method of producing heat transforming effects by circulating in a closed cycle a working substance which occurs in liquid and in vapor states in various parts of the cycle, that step in the method which comprises subjecting the working substance while in liquid state to the action of a basic hydroxide in order to neutralize any acid resulting from decomposition of the working substance.

8. In a mechanically operated heat transforming system of the closed cycle type utilizing a working substance which occurs in liquid and in vapor states in various parts of the system, means for removing moisture from the liquid working substance comprising a hollow member immersed therein, said member having a perforate wall and containing a basic oxide.

9. In a mechanically operated heat transforming system of the closed cycle type utilizing a working substance which occurs in liquid and in vapor states in various parts of the system, and means repeatedly effecting contact of the liquid working substance with material having an affinity for water thereby to "dry" said working substance said means comprising a series of perforated containers

for said material immersed in the liquid working substance.

10. In a mechanically operated refrigerating system of the closed cycle type utilizing a volatile liquid as the refrigerant and having chambers in which a part of the refrigerant gathers in liquid form, and means disposed in said chambers for extracting moisture from said liquid refrigerant and for neutralizing acids resulting from decomposition of the refrigerant, said means comprising perforated containers inclosing a chemical substance adapted to supply hydroxyl ions.

11. In a mechanically operated refrigerating system of the closed cycle type utilizing a volatile liquid as the refrigerant and having a lubricating system containing lubricant, and means comprising containers of reticulated material disposing moisture absorbing and acid neutralizing material in contact with the liquid refrigerant and with the lubricant in order to stabilize both the refrigerant and the lubricant.

12. A closed cycle refrigerating system having a compressor, an evaporator, and a condenser, said evaporator containing liquid refrigerant, and a container immersed in the liquid refrigerant in one of said elements and enclosing a basic oxide for maintaining the refrigerant in a substantially "dry" and stable condition.

13. A closed cycle refrigerating system comprising an evaporator containing liquid refrigerant, a compressor, said compressor withdrawing vaporized refrigerant from said evaporator, a condenser into which said compressor discharges, an expansion device between said condenser and said evaporator, a chamber for condensed refrigerant between said condenser and said device, and containers with stabilizing chemicals therein immersed in the liquid in said evaporator and said chamber.

14. A closed cycle refrigerating system comprising an evaporator containing liquid refrigerant, a compressor, said compressor withdrawing vaporized refrigerant from said evaporator, a condenser into which said compressor discharges, an expansion device between said condenser and said evaporator, a chamber for condensed refrigerant between said condenser and said device, said compressor having a lubricating system, and containers of reticulated material having lumps of a basic oxide therein immersed in the liquid of said refrigerating and of said lubricating systems to maintain both the lubricant and the refrigerant in stable condition.

15. In a mechanically operated refrigerating system having heat transforming means and a compressor provided with a lubricating system for lubricating the parts thereof, means disposing moisture absorbing and acid

neutralizing material in contact with the lubricant to stabilize the same.

16. In a mechanically operated refrigerating system having heat transforming elements and including a compressor having a sump containing lubricant, means subjecting said lubricant to the action of a basic oxide to maintain the same in stable condition.

17. In a mechanically operated refrigerating system having heat transforming means and including a compressor having a sump containing lubricant, a container with one or more perforated walls in said sump, said container having a substance therein adapted to supply hydroxyl ions to said lubricant.

18. In a mechanically operated refrigerating system having heat transforming means, a compressor having a sump containing lubricant, and a reticulated container having calcium oxide therein, said container being disposed in said sump.

Signed by me at Detroit, Wayne County, Michigan, this 14th day of June, 1926.
